UNITED STATES PATENT OFFICE.

GEOERGE A. WEIDLICH, OF BATTLE CREEK, MICHIGAN, ASSIGNOR TO A-B STOVE COMPANY, OF BATTLE CREEK, MICHIGAN.

SPRAY-NOZZLE.

1,254,748.

Specification of Letters Patent. Patented Jan. 29, 1918.

Application filed March 14, 1917. Serial No. 154,834.

To all whom it may concern:

Be it known that I, GEORGE A. WEIDLICH, a citizen of the United States, residing at Battle Creek, Michigan, have invented certain new and useful Improvements in Spray-Nozzles, of which the following is a specification.

This invention relates to a spray nozzle.

The objects of this invention are:

10 First, to provide a head for a spray nozzle by means of which any character of spray from a very fine spray to a single jet or stream may be obtained.

Second, to provide a nozzle of the kind described, which will not easily become clogged.

Third, to provide a head for a spray nozzle which is simple in structure and cheap to manufacture.

20 Further objects, and objects relating to details and economies of construction and operation will definitely appear from the detailed description to follow.

I accomplish the objects of my invention 25 by the devices and means described in the following specification. The invention is clearly defined and pointed out in the claims.

30 A structure constituting a preferred embodiment of my invention is illustrated in the accompanying drawings forming a part of this specification, in which:

Figure I is a longitudinal section through the center of my improved spray nozzle, 35 showing the cap adjusted to produce a single stream.

Fig. II is a longitudinal transverse section similar to Fig. I showing the cap in a position adjusted to produce a spray.

40 Fig. III is an enlarged detail section on a line corresponding to line 3—3 of Fig. II.

Fig. IV is an end view of the nozzle with the cap removed.

Fig. V is an enlarged detail section on a 45 line corresponding to line 5—5 of Fig. I.

In the drawings similar reference characters refer to similar parts throughout the several views and the sectional views are taken looking in the direction of the little 50 arrows at the ends of the section lines.

Referring to the drawing, the barrel-like body 1, which in the structure illustrated is slightly tapered, has an internally threaded enlargement 2 at its larger end, adapted to 55 connect with the threaded nipple of a cou-

pling member, and an externally threaded head 3 at its smaller end. The passage through the barrel is uniformly tapered and terminates in an enlargement or chamber within the head constricted by an annular 60 inwardly extending rib 4. The end of the head 3 is flat and provided with two discharge apertures, one of which, 5, is concentric or central therewith, and the other of which, 6, is eccentric thereto, that is, it 65 is disposed to one side of the central hole 5.

An internally threaded cap or tip 7 is threaded for adjustment upon the head 3 and is provided with an inner flat end wall 8 which co-operates with the flat end of the 70 head 3 to produce a swirl chamber. The cap 7 is provided with an outwardly beveled discharge aperture 9 which is adapted to register with the discharge aperture 6 in the top of a nozzle 12 when the cap 7 is adjusted to 75 its innermost position whereby the nozzle will discharge a single solid jet or stream. When the cap 7 is rotated to unscrew it from the head 3 the aperture 9 is moved out of 80 register with the aperture 6 and the size of the swirl chamber between the end of the nozzle and the cap is gradually increased, thereby varying the character of the spray produced. As the cap 7 is unscrewed from the head 3, the central discharge opening 5 85 is uncovered, the portage of the head is increased. A lug 10 depending from the flange 11 of the cap coacts with the pin 12 secured to the head of the nozzle to limit the movement of the cap. 90

My improved spray nozzle is simple and economical in its parts. It is very efficient in use and may be readily adjusted to vary the character of the spray and further it is 95 not likely to become clogged. I have illustrated an embodiment or adaptation of my improvements such as is suitable for lawn hose or for the spraying of fruit trees and the like.

I have not attempted to illustrate or describe certain modifications which might be desirable for other adaptations as I believe the disclosure made will enable those skilled in the art to which my invention relates to embody or adapt the same as may be desired. 100 105

Having thus described my invention, what I claim as new and desire to secure by Letters Patent is:

1. In a spray nozzle, the combination of a body member provided with a head hav- 110

- ing a flat face with a centrally disposed discharge orifice and an eccentrically disposed discharge orifice, said body having a passage therethrough terminating in an enlarged head chamber, said head chamber having an annular rib providing a constriction spaced from the end thereof, a tip threaded for adjustment upon said head and having a flat face coöperating with the flat face of said head and provided with an outwardly expanded discharge orifice disposed eccentrically and adapted to register with the eccentrically disposed discharge orifice of said head when the tip is in one position, and coacting stops on said head and tip limiting the rotating movement of said tip, for the purpose specified.
2. In a spray nozzle, the combination of a body member provided with a head having a flat face with a centrally disposed discharge orifice and an eccentrically disposed discharge orifice, a tip threaded for adjustment upon said head and having a flat face coöperating with the flat face of said head and provided with a discharge orifice disposed eccentrically and adapted to register with the eccentrically disposed discharge

orifice of said head when the tip is in one position, for the purpose specified.

3. In a spray nozzle, the combination of a body member provided with a centrally disposed discharge orifice and an eccentrically disposed discharge orifice, and a tip threaded for adjustment upon said head and having a discharge orifice disposed eccentrically, for the purpose specified.

4. In a nozzle, the combination of a body member provided with a flat discharge face having a central discharge orifice, and a second discharge orifice disposed at one side thereof, and a cap mounted on said body for rotative and axial adjustment and provided with a discharge orifice disposed at one side of its center and adapted to be brought into register with the second discharge orifice of said body member.

In witness whereof, I have hereunto set my hand and seal in the presence of two witnesses.

GEORGE A. WEIDLICH. [L. S.]

Witnesses:

A. J. REEDY,
A. B. PURDY.
